UNITED STATES PATENT OFFICE.

NICHOLAS COLLIGNON AND CLAUDIUS O. COLLIGNON, OF CLOSTER, N. J.

IMPROVED FOLDING CHAIR.

Specification forming part of Letters Patent No. 96,778, dated November 16, 1869.

To all whom it may concern:

Be it known that we, NICHOLAS COLLIGNON and CLAUDIUS O. COLLIGNON, of Closter, in the county of Bergen and State of New Jersey, have invented a new and useful Improvement in Folding Chairs; and we do hereby declare that the following is a full, clear, and exact description thereof, which will enable others skilled in the art to make and use the same, reference being had to the accompanying drawings, forming part of this specification.

This invention relates to chairs which fold up into a small space, whereby they are rendered much more convenient for transportation and storage than chairs of ordinary construction; and it consists in the peculiar arrangement and combination of parts, as hereinafter more fully described.

In the accompanying sheet of drawings, Figure 1 represents a side elevation of the chair, as when ready for use. Fig. 2 shows the chair as folded up. Fig. 3 is a back side elevation.

Similar letters of reference indicate corresponding parts.

A is the back, the sides of which extend to the floor, and form the front legs, B B.

C C are the back legs.

D represents the seat, and E represents a brace on each side which is pivoted to the front and back legs, as seen in the drawings. The seat is pivoted or jointed to the side pieces, which form the back and front legs, as seen at f, and to the back or rear legs, as seen at g. These joints may be formed by short pivots or bolts, or by rods extending across from leg to leg of the chair, as may be deemed best.

A suitable number of rounds, h, may connect the back legs, C, and also the front legs, H, together. The back, as well as the other parts of the chair, may be finished in any style to suit the taste. It will be seen that when the seat is raised, the upper ends of the back legs (against which the back of the chair bears in supporting a weight on the chair) are thrown down, and the lower ends are thrown up, and the chair will fold together, as seen in Fig. 2, thus rendering the chair much more useful than ordinary chairs, as it may be laid away when not in use, and may be packed in boxes or in bundles for transportation.

We do not confine ourselves to making chairs on this plan exclusively, as it will be seen that settees may be made to fold in the same manner. We therefore propose to make folding settees as well as folding chairs in this manner. The ends of the back legs may be provided with pins, which shall enter holes in the back where the bearing comes, as at i, should it be considered best to do so.

Having thus described our invention, what we claim as new, and desire to secure by Letters Patent, is—

1. The seat D, pivoted to the front legs, B, and at its rear end to the back legs, C, whereby the several parts are adapted to be folded together, as herein shown and described, for the purpose specified.

2. In combination with the above, the brace E, arranged to operate substantially as described.

NICHOLAS COLLIGNON.

CLAUDIUS O. COLLIGNON.
